UNITED STATES PATENT OFFICE.

WILLIAM J. STOOP, OF WHEELING, WEST VIRGINIA.

METAL-SCRAPING APPARATUS.

Application filed November 24, 1925. Serial No. 71,241.

This invention relates broadly to metal scraping apparatus, and it has for its primary object to provide, in association with a set of reducing rolls, mechanism whereby the surfaces of bars, skelp and similar rolled products or shapes, are scraped for effecting the removal of scale, slivers of metal and like deposits of foreign matter which, rolled into the metal, would result in the production of sheets or other rolled shapes of inferior quality due to thereby-produced surface pittings and imperfections.

A further object is to provide mechanism for scraping from sheet bars and other metal forms flaws and surface imperfections, thereby greatly to improve the product during hot rolling thereof.

And a still further object is to provide a mechanism of the character mentioned which includes scraper blades which are yieldingly presented to the surfaces of the advancing material in such manner that not only is the tendency of the blades to chatter eliminated, but also the biting, gouging and cutting of said blades into the advancing material is prevented.

With these and other objects in view, the invention resides in the features of construction, arrangement of parts and combinations of elements which will hereinafter be fully described, reference being had to the accompanying drawings, in which—

Figure 1 is a partial side elevation of the portion of the invention located at the entrance side of a set of rolls, a power cylinder being also shown in section;

Figure 2 is a top plan view of the same, the roll housings being shown in horizontal section;

Figure 3 is a face view of the same;

Figure 4 is a section on line 4—4, Fig. 2;

Figure 5 is an elevation of the same viewed from the side opposite that shown in Fig. 1;

Figure 6 is a diagrammatic view illustrating the means for controlling the pressure to the power cylinders;

Figure 7 is a cross section of the trip mechanism; and—

Figure 8 is a front elevation of the same.

Referring to said drawings, 1 and 2 indicate the opposite parallel housings, and 3 and 4 the top and bottom rolls, respectively, of a bar mill of the general type with which

the present invention is designed to be associated. Mounted in bearings 5 carried by said housings at the entrance side of the mill and at a suitable elevation above the path of movement of bars in entering between said rolls is a transversely disposed rotary shaft 6; and mounted in bearings 7 located at a suitable lower level than said path is a similar rotary shaft 8. The shaft 6 has keyed thereon between said bearings the sleeve portion 9^a of an arm 9 which extends forwardly therefrom and has a downturned front end 10. Rigidly carried on the rear face of said downturned end portion 10 of the arm 9 is a detachable scraper blade 11 having its lower edge projecting somewhat below the corresponding edge, or end, of said arm. Likewise, the shaft 8 has rigidly mounted thereon a forwardly extending arm 12 similar in form to said arm 9, having its forward end 13 upturned and carrying on its rear face a scraper blade 14 which has its upper edge projecting slightly above the level of the corresponding edge, or end, of said arm 12. Said blades 11 and 14 are designed to be actuated into pressure-exerting scraping relation to the top and under surfaces of sheet bars as the latter are drawn forward, or advanced, through the mill, thereby to effect, by the scraping action, the removal from said surfaces of any scale, slivers, and foreign matter which is borne by said surfaces and which would otherwise be rolled into the bar in advancing between the rolls.

The shaft bearings 5 and 7 are carried by, or form parts of, a frame structure, designated generally by the reference character 15, which is attached to and vertically adjustable on the housings 1 and 2, as by means of bolts 16 disposed in slots 17 provided in said housings. Said frame includes side members 18 which extend forward between the housings to a point adjacent to the rolls 3 and 4, and rigidly mounted on the forward ends of said frame members is a forwardly tapered bar-guide 19 having therein a horizontally elongated tapered opening 20 through which bars to be rolled are accurately guided in their passage to said rolls. Also mounted on said frame rearwardly of the vertical plane in which the shafts 6 and 8 are located, and projecting forwardly between said shafts is a bar-guide 21 similar to the guide 19 through which the bars to be

rolled are guided in their passage to the last mentioned guide.

The shafts 6 and 8 are normally held in positions wherein both scraper blades 11 and 14 carried thereby are withdrawn from the path of travel of the sheet bars between the guides 19 and 21. The means by which the shaft 6 is so held comprises a lever 22 which is fixed intermediate its ends in a substantially horizontal position upon an end of said shaft and which carries upon its outer end a counter weight 23. Having pivoted connection with the forward, or inner, end of said lever, as through the intermediacy of a link 24, is the upper end of a piston rod 25 which projects outward through the upper end of a power cylinder 26. Carried by said rod 25 within the cylinder is a piston 27 which normally occupies a position at or adjacent to the upper end of said cylinder and which is adapted to be actuated by the admitted pressure of compressed air, liquid or steam to move downward for rocking said shaft 6 and the thereby-carried blade-carrying arm 9 to substantially the full line position shown in Fig. 4.

A power cylinder 28 similar to said cylinder 26 is mounted on one of the mill housings above the level of the shaft 8. A piston 29 operable within said cylinder 28 has the lower projecting end of its rod 30 connected through a pivoted link 31 to the end of an arm 32 which is fixed on said shaft 8. The weight of the arm 12, supplemented by the weight of the arm 32, serves normally to maintain the shaft 8 in a position wherein said arm 12 is lowered away from the path of travel of sheet bars, as aforesaid.

Opening into the upper and lower ends, respectively, of the cylinders 26 and 28 are pipes 33 and 34 through which the air, liquid or steam pressure employed, as the case may be, is admitted to said cylinders for actuating the pistons thereof in directions for moving, through the intermediate mechanisms described, the blade-carrying arms 9 and 12 into substantially the full line positions shown in Fig. 4, wherein the blades 11 and 14 are disposed for seating in pressure-exerting scraping relation to the opposite faces of an advancing sheet bar. Said pipes 33 and 34 have open communication with a pipe 35 leading from a control valve 36 which is opened and closed, as by means of a shiftable control lever 37, to the passage to said pipe 35 of the pressure fluid from a pressure supply pipe 38. In the closed position of said valve the pressure fluid within the cylinders is permitted to exhaust or escape through an exhaust pipe 39 leading from said valve, thereby to permit the pressure actuated parts described to resume their normal positions.

The shifting movement of the lever 37, whereby the passage of the pressure fluid to and from the cylinders is controlled, is

effected automatically through the intermediacy of a trip mechanism which includes a trip-lever 40 pivoted intermediate its ends on the exit side of the mill below the path of travel of the sheet bars. As herein shown, said trip lever is pivotally mounted on the inner end of a rearwardly directed stationary arm 41 carried by a supporting bracket 42 which is bolted to the mill housings. Said bracket also serves as a support for the lower of two horizontal parallel guide plates 43 and 44 between which the sheet bars are advanced in passing from between the rolls of the mill. Said trip-lever, which is of substantially bell-crank form, normally occupies a position in which its upper arm 40a is inclined upwardly and forwardly. In said position, said arm projects across the guide space located between the plates 43 and 44, being directed through a slot or opening 45 provided therefore in the lower plate 43 and into or through a slot or opening 46 provided therefor in the upper plate 44. Said trip lever, which is normally held in the position described by means of a retractile coil spring 47 attached at one end to the lower arm of the lever and at its opposite end to a suitable stationary part of the structure, as to a lug 48 carried by the bracket 42, has the end of said lower arm connected by a pivoted link 49 to a lever 50 at a point intermediate the ends of the latter. Said lever 50 has its lower end pivotally mounted upon a stationary member, as the bracket-like supporting member 51 mounted on the mill housings below the bracket 42. Formed on the upper end of said lever 50 is a laterally directed finger 52 which, when said lever is rocked rearwardly, is adapted to enter a pocket 53 formed on the outer end of the operating lever 37 of the pressure control valve 36 which is suitably supported over said support 51, and to swing said valve to the position in which it is open to the passage of pressure fluid to the cylinders.

As hereinbefore indicated, as an advancing sheet bar emerges from between the rolls of the mill, its front end strikes the upper arm 40a of the trip-lever and forces the latter to a lowered position within the opening 45 wherein the bar passage between the guide plates 43 and 44 is cleared. The said lowered position of said trip lever is maintained throughout the passage of the sheet-bar thereover, during which time the bar scraper blades 11 and 14 are maintained in scraping relation to the faces of said bar by the actuating pressure admitted to the cylinders by the valve 36 which is open to the passage of said pressure during said time. When the sheet bar has passed from overlying relation to the trip lever, the latter is actuated by its spring 47 to resume normal position, swinging the lever 50 outward, whereby the valve control lever 37 is

returned to its outwardly swung position for closing the inlet passage of the valve 36 and for opening the exhaust passage of said valve.

5. What is claimed is—

1. A sheet bar scraper comprising a pair of aligned rotary shafts mounted each upon opposite sides of the path of travel of sheet bars to a set of reducing rolls, a forwardly extending arm carried by each of said shafts and having ends extending inwardly at right angles to the path of travel of said bars, said ends of the arms forming opposed jaw members, scraper blades carried by said jaw members, and means to rotate the shafts and thereby the arms toward each other and into engagement with said sheet bars whereby to exert a scraping action to remove foreign matter from said bars.
- 10 2. A sheet bar scraper comprising a pair of aligned rotary shafts mounted each upon opposite sides of the path of travel of sheet bars to a set of reducing rolls, a forwardly extending arm carried by each of said shafts

having ends extending inwardly at right angles to the path of travel of said bars, said ends of the arms forming opposed jaw members, scraper blades carried by said jaw members, means to rotate the shafts and thereby the arms into engagement with the sheet bars, and means to yieldably hold the arms in engagement with the bars. 25

3. A sheet bar scraper comprising a pair of aligned rotary shafts mounted each upon opposite sides of the path of travel of sheet bars to a set of reducing rolls, a forwardly extending arm carried by each of said shafts having ends extending inwardly at right angles to the path of travel of said bars, said ends of the arms forming opposed jaw members, scraper blades carried by said jaw members, means to rotate the shafts and thereby the arms into engagement with the sheet bars, and pneumatic means to yieldably hold the arms in engagement with the bars. 30 35 40 45

In testimony whereof, I affix my signature.

WILLIAM J. STOOP.
